CLAIM

The ornamental design for a telescopic discharge system for sump pumps and the like, substantially as shown and described.

DESCRIPTION

FIG. 1 shows a front view of a telescopic discharge system for sump pumps and the like, according to the present invention, as moved to the fully extended orientation, the side and back views being substantially the same, given the cylindrical nature of the system.

FIG. 2 shows a cross-sectional view of FIG. 1, in a best mode format, but the interior portions of the assembly form no portion of the claimed design.

FIG. 3 shows an enlarged front view of the system of FIG. 1, as moved to a more compact, longitudinally shorter orientation, collapsed as selected by the user; and,

FIG. 4 shows a cross-sectional view of FIG. 3, in a best mode format, but the interior portions of the assembly form no portion of the claimed design.

Broken lines at the lower terminal portion of the article illustrate threaded portions forming no portion of the claimed design. Broken lines across the circumference of the drawing illustration band claims and like functional structure forming no portion of the claimed design.
